UNITED STATES PATENT OFFICE.

LEWIS PENWELL, OF CHICAGO, ILLINOIS, ASSIGNOR TO A. B. C. TRANSIT REFRIGERATION COMPANY, OF CHICAGO, ILLINOIS, A CORPORATION OF DELAWARE.

REFRIGERATING SYSTEM.

Application filed June 3, 1921. Serial No. 474,610.

To all whom it may concern:

Be it known that I, LEWIS PENWELL, a citizen of the United States, residing at Chicago, in the county of Cook and State of Illinois, have invented new and useful Improvements in Refrigerating Systems, of which the following is a specification.

This invention relates in general to refrigerating apparatus, and more particularly to 10 that type in which brine or other cooled liquid is employed as the refrigerating medium.

One of the primary purposes of my present invention is to provide an apparatus of 15 the character indicated, the principles of which may be embodied either in stationary installations, such as small cold storage plants, or in portable installations, such as refrigerator cars, refrigerator trucks and 20 the like.

Another object is to provide an apparatus which will be extremely simple in construction, and therefore economical to manufacture and install, and one which will be substantially automatic in operation so as to require a minimum of attention.

Another object is to provide an apparatus which will be highly efficient in operation, and capable of cooling chambers of substantial cubical content with the expenditure 30 of a very small amount of power.

More specifically, my invention contemplates a circulation of the cooling medium through the chamber to be cooled, partially 35 by positive application of power, and more largely by automatic siphonic action, the apparatus being so arranged that the cooling medium is circulated near the ceiling of the chamber so as to secure a maximum and a 40 uniform cooling effect within the chamber.

For the purpose of facilitating an understanding of my invention, I have illustrated on the accompanying drawings, one simple embodiment thereof, from an inspection of 45 which when considered in connection with the following description, the principles of my invention and many of its inherent advantages should be readily understood and appreciated.

50 Referring to the drawings:

Fig. 1 is a longitudinal sectional view through an apparatus embodying my invention on the line 1—1 of Fig. 2;

55 Fig. 2 is a horizontal sectional view on the line 2—2 of Fig. 1; and

Fig. 3 is a vertical sectional view on the line 3—3 of Fig. 1.

Referring now to the drawings more in detail, reference character 5 indicates generally the cooling chamber in which the produce to be cooled and preserved is stored. This chamber may be of any preferred size and construction suitable either for stationary or portable uses, and the walls thereof have incorporated in their structure, heat-insulating material of well known or preferred character.

At the ends of the cooling chamber, there are provided the brine tanks 6 and 7 respectively, also having heat-insulated walls and 70 adapted to contain brine or other preferred cooling medium. In the form of the invention herein illustrated, which is designed more particularly as a stationary installation, the brine tanks are relatively low and 75 shallow so that their tops are disposed substantially at the level of a wagon body, thereby making the delivery of ice from the wagons directly into the tanks through the openings 8 very convenient. These open- 80 ings are sealed by the usual insulated covers 9, upon the removal of which the ice may be slid from the wagons directly into the brine tanks. For a portable installation, such as 85 a refrigerator car or truck, these tanks will be considerably deeper and narrower longitudinally of the car or truck, and would 90 preferably extend approximately to the top of the cooling chamber. The size and shape of the tanks, however, are of no particular 95 moment in so far as the principles of my invention are concerned. The cooling medium which I contemplate using in the installation shown is brine at low temperatures resulting from the melting of the ice with 100 which the tanks 6 and 7 are charged, the melting of the ice being expedited by the introduction into the tanks of quantities of salt, which are preferably introduced into the tanks simultaneously with the ice. In 105 some systems, particularly stationary installations, other cooling medium than brine might be employed, and instead of charging the tanks with ice and salt, the cooling medium might be reduced to the desired temperature by a refrigerating apparatus of any preferred construction.

For the purpose of circulating the refrigerating medium through the cooling chamber 5, adjacent the ceiling thereof, I have 110

provided an apparatus, which will now be described. This apparatus comprises a main positive flow pipe 11 having its intake end 12 communicating with the interior of the tank 6 some distance from the bottom thereof, and its delivery end 13 similarly communicating with the interior of the tank 7. Within the cooling chamber 5, this pipe extends upwardly along one of the end walls, thence longitudinally of the chamber along the ceiling, and thence downwardly adjacent the other end wall. Interposed in this pipe, preferably in proximity to the tank 6 is a rotary pump 14 driven in any suitable manner, preferably by an electric motor 15. The cooling medium is withdrawn from tank 6 by the pump and delivered through the pipe 11 into tank 7, thus tending to increase the liquid level in tank 7 and diminish the level in tank 6. For the purpose of returning the liquid from tank 7 to tank 6, I have provided a plurality (in the present instance 7) of siphonic return pipes 16, each extending through the cooling chamber 5 substantially parallel with the pipe 11 and communicating at each end with the interiors of the tanks 6 and 7 respectively, but at a lower level than the intake and delivery ends 12 and 13 of the pipe 11. The relative positions of the ends of these pipes will be apparent from Figs 1 and 3, since from these figures it will be observed that the delivery ends 17 of the pipes 16 are disposed considerably nearer the bottom of the tank 6 than is the intake end 12 of the pipe 11. Similarly, the intake ends 18 of pipes 16 in the tank 7 are nearer the bottom than the delivery end 13 of pipe 11. This difference in the level of communication between the tanks and the main flow and return pipes insures that the ends of the return pipes will always be submerged in the liquid since, should the liquid level in tank 6 be withdrawn through pipe 11 until the level falls below the intake end 12, the withdrawal of liquid from this tank will cease, leaving the lower ends 17 of pipes 16 still submerged.

The return flow of cooling medium from the tank 7 to tank 6 takes place through pipes 16 by siphonic action, and as the liquid level rises in tank 7 through delivery of cooling medium thereto from the tank 6 through pipe 11, the differences in the liquid level in the two tanks will cause a return flow by siphonic action from tank 7 to tank 6 through pipes 16. This flow, however, will not continue sufficiently to reduce the liquid level in tank 7 below the intake ends 18 of the siphonic pipes 16 for the reason that before this point is reached, the liquid level in tank 6 will be sufficiently higher to stop the siphonic flow. The return pipes 16 are always filled with liquid and the siphoning action will take place when-

ever the level in tank 7 exceeds the liquid level in tank 6.

For the purpose of withdrawing the air from pipes 16 to initiate the siphonic flow, and to fill the pipe 11 with liquid so that the pump will have very little resistance to overcome, I have provided a manually operable pump 19 connected through a suction pipe 21 with each of the pipes 16 and 11, and when the apparatus is to be initially started, this suction pump is manually operated until the air in pipes 16 has been withdrawn and replaced by the liquid cooling medium from the tanks, whereupon the siphonic action will begin. It should be noted at this point that the air suction pump is connected with the pipes 16 and 11 at their highest point, thus insuring the withdrawal of all of the air from the pipes and preventing the leaving of air bubbles in the pipes which might break their siphonic action. When it becomes necessary to recharge the tanks with ice and salt, the liquid therein which has been raised to a higher temperature than desirable, is withdrawn through a drain pipe 22 equipped with a shutoff valve 23, the point of communication of this pipe with tank 6 being above the intake end 12 of pipe 11 so that there will always remain in the tanks sufficient liquid to insure submergence of the ends of the pipes 16. Tank 7 may also be equipped with a drain pipe if desired, but it is unnecessary for the reason that the surplus liquid in tank 7 will be siphoned into the tank 6 as the surplus from this tank is withdrawn through the pipe 22.

In the operation of my apparatus, the cooled medium is positively circulated in one direction through the pipe 11 by the pump 14 and return flow automatically takes place by siphonic action through the return pipes 16. The cooling chamber is therefore subjected to the cooling action of all of the pipes, and since the cooling medium only flows from one tank to the other, the distance that it travels within the cooling chamber is relatively small as compared with systems in which the cooling medium is circulated back and forth through long coils and becomes materially heated so that its cooling action is much reduced before it is withdrawn from the cooling chamber. My improved system, therefore, is highly efficient, and is capable of reducing the temperature in the cooling chamber much more quickly than would be possible by the circulation of a cooling medium through long coils. Furthermore, sharp elbows and turns are entirely eliminated from the cooling pipes, thus reducing the expense of installation, and also reducing pipe friction, the pipe friction being further reduced by the fact that the cooling medium flows slowly through the pipes, as distinguished from the rapid flow in

closed coil installations. In this system also, instead of relying upon transmission of heat through closed pipes in the tanks, the medium is delivered directly from the cooling 5 pipes into the tanks, where it mingles with the cold medium and this cold liquid is being constantly withdrawn from both tanks, with the result that the liquid in both pipes 16 and 11 is always at a low temperature, 10 and when it leaves the tanks, is at the same temperature as the liquid in the tanks instead of being several degrees warmer as it would be if the heat transference took place through closed coils in the tanks, as is customarily done. Once the system is started 15 in operation, very little power is required to keep it going, for the reason that when the pipe 11 becomes filled with liquid, the pump is working only against the difference in 20 head between the tanks 6 and 7, and this head is necessarily very slight, as the siphonic action through the return pipes tends to maintain the same liquid level in each tank. The aggregate capacity of the pipes 16 being 25 many times greater than the capacity of pipe 11, there is never any danger of accumulating undesirable surplus of cooling medium in the tank 7. A further desirable feature is that the liquid in both tanks is continually agitated by the withdrawal and delivery thereto of liquid at a plurality of points, consequently, there can be no recirculation of heated liquid, and this result is effected without the use of mechanical agitators.

My improved apparatus is therefore extremely simple in construction, cheap to manufacture, easy to install, and is highly efficient in operation. The power required 40 to operate it is slight, and once it has been started, it will continue to operate indefinitely without attention other than the periodical replenishing of the supply of ice and salt in the tanks, and the withdrawal of the 45 surplus heated liquid through the pipe 22.

It is believed that my invention, its construction, mode of operation, and many of its inherent advantages will be understood and appreciated from the foregoing without 50 further description, and while I have shown and described a preferred embodiment of the invention, obviously, the details of construction may be varied within wide limits without departing from the essence of the 55 invention as defined in the following claims.

I claim:

1. In a refrigerating system, the combination of a cooling chamber, a plurality of tanks disposed below the upper portion of 60 said chamber adapted to contain a refrigerating medium, and means for circulating said medium through said chamber, said means comprising a plurality of pipes extending through the upper portion of said chamber and communicating at each end

with the respective tanks below the liquid level therein and means for positively delivering medium through said chamber from one tank to the other.

2. In a refrigerating system, the combination of a plurality of tanks adapted to contain a refrigerating medium, means for positively delivering said medium from one tank to another, and a return pipe disposed intermediate its ends above the level of said tanks and communicating with the interior of both tanks below the liquid level therein whereby said medium is returned to said first tank by siphonic action.

3. In a refrigerating system, the combination of a cooling chamber, a plurality of tanks adapted to contain a refrigerating medium, means for causing a positive delivery of said medium from one tank to another through said chamber, and siphonic means for producing a reverse flow of medium 85 from said second to said first mentioned tank through said chamber.

4. In a refrigerating system, the combination of a cooling chamber, a plurality of tanks adapted to contain a refrigerating medium, means for establishing a difference in liquid level in said tanks, and means extending through said chamber above the liquid level in said tanks tending to reestablish a common liquid level between the tanks.

5. In a refrigerating system, the combination of a plurality of tanks adapted to contain a liquid refrigerating medium, a pipe connecting said tanks, a pump for delivering liquid through said pipe from one tank to another to produce a difference in liquid level in said tanks, and a siphonic return pipe communicating with both tanks below the liquid level therein through which the liquid levels in said tanks tend to equalize the central portion of said return pipe being disposed above the liquid level in said tanks.

6. In a refrigerating system, the combination of a cooling chamber, a plurality of tanks adapted to contain a liquid refrigerating medium, a plurality of circulating pipes extending through said chamber above the level of the liquid in said tanks and communicating with the respective tanks, and means for positively delivering liquid through one of said pipes from one tank to the other, the liquid being circulated in the reverse direction through another pipe by siphonic action.

7. In a refrigerating system, the combination of a cooling chamber, tanks disposed at opposite ends and near the bottom thereof, a pipe disposed near the ceiling of said cooling chamber and communicating at each end with said tanks, a pump for causing a delivery of liquid through said pipe from one of said tanks to the other, and another pipe near the ceiling of said chamber dis-

posed substantially parallel to said first mentioned pipe and communicating with each of said tanks below the liquid level therein through which liquid is returned from the 5 second to the first mentioned tank by siphonic action.

8. In a refrigerating system, the combination of a cooling chamber, a pair of tanks at opposite ends of said chamber adapted to 10 contain a liquid refrigerating medium, a pipe extending through said chamber and communicating at its ends with the respective tanks, and another pipe extending through said chamber above the liquid level 15 in said tanks and communicating at its ends with the respective tanks below the level of the communication of said first mentioned pipes with said tanks.

9. In a refrigerating system, the combination of a cooling chamber, a plurality of liquid containing tanks, a pipe extending through said cooling chamber and communicating at its intake end with one of said tanks remote from the bottom thereof and 25 also communicating at its delivery end with the other tank, and a return pipe extending through said chamber above the liquid level in said tanks and having both ends thereof 30 communicating with the respective tanks below the level of the intake end of said first mentioned pipe.

10. In a refrigerating system, the combination of a cooling chamber, a pair of liquid containing tanks disposed at opposite 35 ends of said chamber, a pipe communicating with each of said tanks and extending through said chamber, a pump for delivering liquid through said pipe from one of said tanks to the other, and a plurality of 40 pipes extending through said chamber and communicating at their ends with said respective tanks below the liquid level therein through which liquid is returned from said second to said first mentioned tank by 45 siphonic action, the capacity of said second mentioned pipes being greater than the capacity of said first mentioned pipe.

11. In a refrigerating system, the combination of a cooling chamber, a liquid containing tank at each end of said chamber remote from the top thereof, a pipe extending through said chamber and communicating with each of said tanks, a pump for delivering liquid through said pipe from one of 55 said tanks to the other, a plurality of return pipes extending through said chamber nearer the top thereof and communicating with each of said tanks below the liquid level therein, and means for withdrawing the air 60 from said return pipes.

12. In a refrigerating system, the combination of a cooling chamber, a plurality of tanks adapted to contain a refrigerating

medium, means for causing a positive delivery of said medium from one tank to another, and siphonic means for producing a reverse flow of medium from said second to said first mentioned tank through said chamber. 65

13. In a refrigerating system, the combination of a cooling chamber, a plurality of tanks adapted to contain a refrigerating medium, means for positively delivering medium from one of said tanks to the other, and means extending through the upper portion 70 of the chamber and establishing communication between said tanks below the liquid levels therein whereby said cooling medium 75 is returned to said first tank.

14. The combination with a refrigerator or the like having an ice compartment; of a siphon arranged in the chamber of the refrigerator and disposed around the walls thereof, and water traps or seals at the lower ends of said siphon, one of which is designed 80 to receive the water from the melting ice and the other of which is shut off from direct communication therewith and communicates therewith only through the siphon whereby 85 the same will circulate through the siphon 90 and the other provided with a drain.

15. In a refrigerator, a siphon extending along the inside of the side and top walls of the same and having a large heat absorbing surface exposed to the provision chamber, and seals at the lower ends of said siphon and one being disposed to receive the water from the melted ice and the other communicating therewith only through the siphon 95 and means for filling said siphon. 100

16. In a refrigerator, a siphon extending along the side and top walls of the same at the inside and of such form and arrangement that a large heat absorbing surface is presented to the provision chamber, and seals 105 at the lower ends of said siphon and one being disposed to receive the water from the melted ice and the other receiving water only from the discharge end of the siphon, the short leg of the siphon being directly in communication with the drip water tank or water supply and the outlet in the long leg communicating therewith only through the siphon. 110

17. In a refrigerator, a siphon extending along the inside of the walls and top of the same and having a large heat absorbing surface disposed adjacent to the provision chamber of the refrigerator, the ends of the siphon being of the same length and seals 115 at the lower ends of said siphon and one being disposed to receive the water from the melted ice and the other communicating therewith only through the siphon, said seals 120 being disposed at the same level.

LEWIS PENWELL.
